126,196

DESIGN FOR A COMBINED LAMP AND RADIO RECEIVING SET

Daniel J. Crowley, Grosse Pointe, and Earl W. Dulmage, Detroit, Mich., assignors, by mesne assignments, to said Daniel J. Crowley

Application December 21, 1940, Serial No. 97,520

Term of patent 14 years

To all whom it may concern:

Be it known that we, Daniel J. Crowley and Earl W. Dulmage, citizens of the United States of America, residing at Grosse Pointe, in the county of Wayne and State of Michigan, and Detroit, in the county of Wayne and State of Michigan, respectively, have invented a certain new, original, and ornamental Design for a Combined Lamp and Radio Receiving Set, of which the following is a specification, reference being had therein to the accompanying drawing, forming a part thereof, wherein the figure is an elevational view of a combined lamp and radio receiving set, showing our new design.

The side opposite to the side illustrated in the drawing is the same in appearance, with the exception that the window or opening is eliminated. The two members projecting downwardly from the head of the design illustrated in the figure are tubes which form a part of the radio receiving circuit. The dominant features of our design reside in the portions shown in full lines.

We claim:

The ornamental design for a combined lamp and radio receiving set, substantially as shown and described.

DANIEL J. CROWLEY.
EARL W. DULMAGE.
